ELECTRIC SWITCH

Hugh M. Rockwell, Freeport, N. Y.

Application November 15, 1932, Serial No. 642,716

8 Claims. (Cl. 200—59)

This invention relates to improvements in circuit making and breaking devices, and has particular reference to such devices of the "push and pull" type, that is switches having members capable of relative longitudinal movement.

An important object of the invention is to provide a switch of the above mentioned character which will be extremely simple in construction, and with which current-conducting wires may be quickly and easily connected.

Another object is to provide such a switch in which the wire connecting means constitute switch contacts for engagement by one or more contact members of the other relatively movable part.

Another object is to provide such a switch which will be particularly well adapted for use in stop light circuits of vehicles in which the switch is automatically actuated as the brakes of the vehicle are applied and released.

Another object is to provide such a switch which will form a part of the operative connection between the brake pedal and the brakes of a vehicle.

Another object is to provide such a switch which can be very easily and quickly applied to any commercial vehicle with a minimum amount of labor.

Such stop light switches as have been in use prior to this invention have comprised a main body portion rigidly mounted upon the vehicle frame or floor board, and a movable contact member associated with said body portion and connected either to the brake pedal or to the brake rod. There are many specifically different kinds of switches commercially available, but due to differences of design of different makes of vehicles, these various switches are not interchangeable. The original installations and

replacements of such switches have therefore involved considerable labor, and in these arrangements in which the movable member is connected to the brake rod by means of a clamp, such operative connections have sometimes become loose. Another objection has arisen from the employment of one or more strong springs in the switch for returning the movable member to its normal opened position, this adding considerable resistance to the movement of the pedal or the like in applying the brakes. These objectionable features of the prior art devices are overcome by the present invention, which provides a simplified form of stop light switch which can be economically manufactured, and which will

be thoroughly dependable, strong and durable in service.

With the foregoing and other objects, features, and advantages in view, the invention resides in the novel features of construction, combinations, and arrangement of parts hereinafter set forth, shown by way of illustration in the accompanying drawings, and specifically pointed out in the appended claims.

In the drawings,

Figure 1 is a side elevation of one form of switch embodying the invention and shown diagrammatically as applied to the braking system of a vehicle;

Fig. 2 is a vertical longitudinal sectional view through the switch per se, on an enlarged scale, and showing the parts in their normal position;

Fig. 3 is a similar view with the parts in their circuit closing position;

Fig. 4 is a detail perspective view of the movable contact member;

Fig. 5 is a vertical transverse sectional view on line 5—5 of Fig. 3;

Fig. 6 is a horizontal sectional view on line 6—6 of Fig. 2;

Fig. 7 is a vertical longitudinal sectional view through another form of switch embodying the invention;

Fig. 8 is a horizontal sectional view through the modified form of switch shown in Fig. 7;

Fig. 9 is a fragmentary view similar to Fig. 7, but show the parts in circuit-closing relation;

Fig. 10 is a vertical transverse sectional view taken on line 10—10 of Fig. 9; and

Fig. 11 is a vertical transverse sectional view taken on line 11—11 of Fig. 9.

In Fig. 1, one form of improved switch 10, embodying the invention, has been shown in association with conventional portions of an automobile braking system, wherein a brake pedal 11 is pivoted at 12 and connected by means of brake rods or links 13 to the levers 14 of the brakes 15, only one of which has been illustrated. As the pedal 11 is depressed, the brake rods are drawn forwardly to actuate the brake which may be of any ordinary or preferred type. The switch 10 is interposed between the foot pedal 11, and the brake 15 in such a manner as to constitute a part of the operative connection, and said switch is adapted to transmit the braking pressure.

Referring more particularly to Figs. 2 to 6 inclusive it will be seen that the switch 10 includes a main body portion 16 and a co-operative member 17, which are movable together, and with reference to each other, their relative movement

being limited. The main body portion 16 comprises a substantially cylindrical socket 18, having a forwardly extending yoke 19 suitably apertured at 20 for the reception of a clevis pin 21, 5 or the like, by means of which it may be connected to the pedal 11. The socket portion 18 is further characterized by a recess 22, which extends inwardly from the rear surface thereof, and which is screw threaded as at 23 for the reception 10 of a threaded portion 24 of an insulation block 25. Said block 25 may be formed of any suitable dielectric material, for example fabric-base bakelite, hard rubber, or fibre, and is provided 15 with a substantially central longitudinal bore 26, within which is slidable a sleeve 27 of the co-operating member 17. The sleeve 27 is also formed of dielectric material, and is preferably 20 in the nature of a bushing, whose inner periphery is secured, in any suitable manner, to a metallic sleeve 28 which, in turn, is provided at its inner or forward end with an enlarged circular head portion 29. The head portion 29 is capable of longitudinal or axial movement within the recess 22, and is limited by abutment with the bottom of 25 said recess in one direction, and with the inner end of the threaded member 24 in the other direction. The sleeve 28 is internally threaded as at 30 for connection with the forward end of the brake rod 13, and may be securely locked in relation therewith by means of a lock washer 31 and lock nut 32. While the major portion of the sleeve 28 is preferably cylindrical, its outer or rearward end may be milled off or otherwise 35 formed with a hexagonal or square cross section to accommodate a wrench, whereby adjustment can be made relative to the rod 13, and said end extends outwardly beyond the rearward end of the insulation member 25.

A pair of spaced contact members 33 and 33a 40 are fixed in the dielectric block 25, and preferably disposed at the opposite sides of the bore 28, and said bore is provided with a groove 34 at a suitable point in its length, in which portions of said contact members 33 and 33a are exposed. 45 The contact members 33 and 33a are preferably in the form of cylindrical extensions of screws 35 and 35a respectively which are seated within suitable screw-threaded sockets 36, and preferably disposed below the surface of the dielectric 50 material as best shown in Figs. 5 and 6. The inner ends of said contact members are preferably pointed as at 37, and adapted to extend into longitudinally extending holes 38 and 38a, in which ends of the current-conducting wires 55 39 and 40 respectively are adapted to be received. The pointed ends 37 of the members are adapted to pierce the insulation of the conducting wires and thereby form electrical contact with the metal, at the same time expanding 60 the wire against the walls of the holes 38 and 38a, and said connections are entirely concealed within the dielectric block 25. Extending inwardly from the front surface of the block 25 are a plurality of recesses 41, within each of which is 65 disposed a compression spring 42, there being six such recesses and springs illustrated in the drawings. The normal arrangement of the parts is shown in Fig. 2, from which it will be evident 70 that the forward ends of the springs 42 bear against the rearward sides of the head member 29 in such a manner as to move said head member into abutting relation with the bottom of the recess 22 in the socket member 18.

The dielectric sleeve 27 is provided with a 75 peripheral groove 43 within which is disposed a

resilient contact member 44 which, as has been shown in Fig. 4, is in the nature of a metallic ring which normally tends to expand. When the parts are in their normal positions, as shown in Fig. 2, the contact connecting ring 44 is disposed in a different plane from the common plane of said contacts 33 and 33a, and the circuit is broken. When, however, the pedal 11 is depressed to actuate the brake the main body portion 16 of the switch is moved longitudinally 10 with reference to the co-operating portion 17, with the result that the ring 44 engages those portions of the contacts 33 and 33a which are exposed in the groove 34, and closes the circuit 15 therethrough. Only a slight amount of movement is necessary to accomplish the making and breaking of the circuit, and by forming the bore 26 with the groove 34 ample provision is made for manufacturing variations both in the diameters and in the distances between the contacts 20 33 and 33a. If desired, the side walls of said groove 34 may be inclined to facilitate passage of the ring 44 in disassembling the parts.

When in use for controlling a vehicle stop light the switch 10 is mounted as previously described in connection with Fig. 1, the yoke portion 20 being attached in a suitable manner to the pedal 11, and the sleeve 23 being secured to the forward end of one of the brake rods or links 13, thus forming an integral part of the 30 operative connection between the pedal and the brake. The wire 39 is inserted in the hole 38, whereupon the screw 36 may be tightened to force the pointed end 37 of the upper contact member 33 into electrical engagement with said 35 wire 39. The opposite end of the wire 39 is connected to the stop light 46 mounted at the rear of the vehicle, said stop light being also connected to ground at 47. The current-conducting wire 40 is similarly connected to the lower contact 40 member 33a, and the rear end is connected to a storage battery 48, or other suitable source of current supply, which is also connected to ground at 49. As the pedal 11 is depressed to actuate 45 brake, the main body portion 16 and co-operating portion 17 are first moved with relation to each other against the action of the compression springs 42 until the forward end of the insulation block 25 abuts against the rear surface of the head member 29. In this condition the expanding ring 44 has been moved into the common plane of the spaced contacts 33 and 33a and in such a manner as to mutually engage the same and close the circuit, and thereafter continued movement of the brake pedal 11 in the 50 same direction will cause the entire switch 10 to be moved as a unit and to transmit the full braking force from the pedal to the brake link. When the foot pressure is released from the pedal 11 the parts return to their normal positions, in which 55 the brakes 15 are released and the springs 42 cause the circuit through the stop light to be again broken within the switch. It will be evident from this that during the early part of the movement of the pedal 11 in applying the brakes only a slight 60 foot pressure is required to compress the springs 42, and that after the limit of relative movement has been reached said springs become ineffective and do not add resistance to the braking pressure after the circuit has been closed.

Aside from the simplicity of the electrical connections in the switch of this invention, a particularly desirable feature resides in the fact that the same may be very readily applied to any commercial vehicle without necessitating the drill- 75

ing of holes or other labor operations which have been necessary in connection with the prior art stop light switches. The proportions of the parts are such that the switch is interchangeable with a standard brake-rod yoke, and in order to apply the same it is only necessary to disconnect the brake-rod and substitute the switch 10 in place of it.

While switch 10 has been shown on the drawings as directly connected to the pedal 11, it is to be understood that this specified location is not necessary, since it may be employed with equal advantage in other locations between the pedal and the brake. Furthermore, the structural details of the switch may be modified in various ways to accommodate it to different installations as will be obvious.

In Figs. 7 to 11 inclusive, one of the numerous possible modifications has been shown by way of example. By referring to these views in detail, it will be seen that the switch therein shown comprises a block 60 of suitable dielectric material of substantially rectangular cross-section, and provided with a pair of spaced contact members 61 and 62. This block 60 is formed with a substantially cylindrical cavity or bore 63, and is partly embraced by and clampingly held in the U-shaped body 64 of a steel strap or yoke, the ends 65 of which are apertured like the yoke 19 for reception of the clevis pin 21 whereby it may be mounted in the brake system of a vehicle just the same as the first described embodiment. A metallic sleeve 66 is fitted for limited sliding movement within the cavity 63 said sleeve being internally bored and screw-threaded for attachment to the brake rod 13. Movement of the sleeve is limited in one direction by shoulder portions 67 engaging against the inner surface of the yoke body 64, and in the opposite direction by a nut 68 which is screwed on the rod 13 and against the outer end of the sleeve 66. Rotation of the sleeve within the block 60 is prevented by key portions 69 outwardly or rearwardly of the shoulder portion 67.

At an appropriate point in its length, the sleeve 66 is circumferentially grooved and fitted with a dielectric collar or bushing 70 which is, itself, grooved at 71 for reception of the resilient contact connector ring 72 substantially like the member 44. Rearwardly of the groove 71 is a longer but shallower groove 73 which provides clearance for those portions of the contact members 61 and 62 which extend partly into the cavity 63. Normally the contact connector ring 72 is entirely out of the plane of the members 61 and 62 and out of contact with them by reason of the pressure of springs 74 disposed in recesses 75 in the end of the sleeve 66. However, when the pedal 11 is depressed to apply the brakes of the vehicle, the yoke 64 is moved against the shoulder portions 67 of the metallic sleeve 66, and as a result, the members 61 are moved into engagement with the contact connector ring 72 closing the circuit. After this initial movement, the breaking force, is transmitted to the rod 13 through the metal members 64 and 66 without imposing any undue strain on the circuit-making and breaking means or their insulating members. It is to be noted that the parts are so arranged that as the circuit is made or broken there will be a slight wiping action between the contact members and the resilient contact-connecting ring, and this insures clean surfaces which render the switch at all times dependable in closing the circuit.

As in the first described embodiment, the contact members 61 and 62 may be pointed at one end to pierce the respective wires 39 and 40, or if desired, they may be provided with other means for receiving or attaching the wires by standard clips or otherwise. In some respects the structure shown in Figs. 7 to 11 inclusive is more preferable than that shown in Figs. 2 to 6 because of its greater strength and economy in manufacture. Nevertheless, it will readily be appreciated that both of these forms embody the same principles of operation and relate to the same generic invention.

The first-described form of the invention was disclosed in my allowed application Serial No. 200,995 of which the present application is a continuation in part and a carrying forward. Obviously the invention is susceptible of further modification in the details of construction, combinations, and arrangement of parts, and the right is herein reserved to make such changes as fall within the scope of the appended claims without departing from the spirit of the invention.

Having thus described my invention, what I claim is:—

1. In a stop light switch for vehicles, a pair of relatively movable coaxial members formed of dielectric material, a pair of spaced contact members screwed in one of said dielectric members at opposite sides of its axis, a resilient contact connecting member carried by the other dielectric member and being adapted to alternately make and break the circuit between said spaced contact members, and mounting means for securing the same in a brake link system wherein the switch will float as a unit and transmit braking forces.

2. In a stop light switch for vehicles, a pair of relatively movable members formed of dielectric material, a pair of spaced contact members carried by one of said dielectric members, a resilient contact connecting member carried by the other dielectric member and being adapted to alternately make and break the circuit between said spaced contact members, and means associated with each of said dielectric members whereby to mount the same directly in a brake link system, said contact members comprising transversely extending studs, and having their inner ends pointed whereby to be capable of piercing the insulation of current-conducting wires to form electrical contact therewith.

3. In a stop light switch for vehicles, a pair of relatively movable members formed of dielectric material, a pair of spaced contact members screwed in one of said dielectric members, a resilient contact connecting member carried by the other dielectric member and being adapted to alternately make and break the circuit between said spaced contact members, and means associated with each of said dielectric members whereby to mount the same in a brake link system, said contact members comprising transversely extending studs, and having their inner ends pointed whereby to be capable of piercing the insulation of current-conducting wires to form electrical contact therewith, the inner ends of said studs and the connected portions of said wires being entirely within the confines of the dielectric material.

4. In a stop light switch for vehicles, a pair of relatively movable members formed of dielectric material, a pair of spaced contact members

screwed in one of said dielectric members, a resilient contact connecting member carried by the other dielectric member and being adapted to alternately make and break the circuit between 5 said spaced contact members, and mounting means associated with each of said dielectric members, said contact members comprising transversely extending studs, and having their inner ends pointed whereby to be capable of piercing 10 the insulation of current-conducting wires to form electrical contact therewith, and said contact connecting members comprising an expansible metal ring disposed in a plane substantially parallel to the common plane of said spaced contact members.

5. In an electric switch, a main body portion, a co-operating member having limited sliding movement with reference thereto, a pair of switch contacts mounted in said body portion, said contacts being separated and insulated from each other, and resilient contact connecting means carried by the co-operating member and adapted to be moved into and out of engagement with said spaced contacts, said switch contacts having 20 piercing means for making electrical connection with a current-conducting wire, said resilient contact connecting means comprising an expansion ring.

6. In an electric switch, a main body portion 30 formed of dielectric material and provided with a substantially central bore, a co-operating member slidable axially in said bore, a pair of cylindrical switch contacts extending transversely in the main body and having exposed portions in 35 said bore, and an expansible ring carried by said co-operating member and adapted to be moved into and out of the common plane of said switch

contacts and to mutually engage the same to make and break the circuit.

7. In an electric switch, a main body portion 5 formed of dielectric material and provided with a substantially central bore, a co-operating member slidable axially in said bore, a pair of cylindrical switch contacts extending transversely in the main body and having exposed portions in 10 said bore, the inner ends of said switch contacts being pointed and adapted to pierce confined current-conducting wires to make electrical connection therewith, and a resilient expansible ring carried by said co-operating member and adapted to be moved into and out of the common plane 15 of said switch contacts and to mutually engage the same to make and break the circuit.

8. A stop light switch of the class described, comprising a body of dielectric material having a substantially central longitudinal bore, a substantially U-shaped metallic strap carrying and partly 20 surrounding said body and adapted for connection in a brake link system, a pair of spaced contact members located in the body and having portions exposed in the central bore, means for connecting said contact members with current conducting wires, a cooperating member having sliding movement within the bore, and also adapted for connection in a brake link system, an insulated contact member carried by said cooperating member and adapted alternately to engage and 25 disengage the contact members to make and break the circuit, and means for limiting the sliding movement of the cooperating member within the bore when the contacts are in engagement, and for transmitting full braking forces through 30 the brake link system.

HUGH M. ROCKWELL.
